NICHOLAS GROEL, OF NEWARK, NEW JERSEY.

Letters Patent No. 70,832, dated November 12, 1867.

IMPROVEMENT IN TRAVELLING-BAGS AND VALISES.

The Schedule referred to in these Letters Patent and making part of the same.

TO ALL WHOM IT MAY CONCERN:

Be it known that I, N. GROEL, of Newark, Essex county, New Jersey, have invented a new and useful Improvement in Travelling-Bags and Valises; and I do hereby declare that the following is a full, clear, and exact description thereof, which will enable others skilled in the art to make and use the same, reference being had to the accompanying drawings, forming part of this specification.

In the accompanying plate of drawings my improvement in travelling-bags or valises is illustrated—

Figure 1 being an exterior view of one corner of a bag or valise protected according to the present invention, and

Figure 2 a section through the said corner.

Similar letters of reference indicate corresponding parts.

A, in the drawings, represents a portion or one corner of one of the frames, upon which a leather bag or valise is ordinarily made. This frame, in the present instance, is shown as made of wood, but may be of iron or other suitable metal or material. B, a portion of the exterior or outside covering of leather attached to the bag-frame A, in the usual manner; and C one of the corners to such exterior leather covering B. This corner, as well as all the corners to the bag, is strengthened and stiffened by a metallic corner-piece, D. These pieces are made of sheet metal struck up of suitable shape to embrace the leather corner shown, to which they are riveted, and to extend around to the wooden frame A, where it is also secured by riveting, or in any other proper manner.

By the above attachment of corner pieces, not only are the leather corners to the bag or valise preserved from wear, and thus rendered more durable, but at the same time are strengthened and stiffened by the attachment of the said corner-pieces to the frame on which the bag or valise is built. In lieu of forming the corner-pieces independent of and separate from the frames on which the bag or valise is made, they may be made as a part of the frames, if they are metal.

I claim as new, and desire to secure by Letters Patent—

As an article of manufacture, the struck-up metallic corner-pieces D, when constructed and applied in the manner described to valises and travelling-bags, for the purpose specified.

NICHOLAS GROEL.
